UNITED STATES PATENT OFFICE

116,213

DESIGN FOR AN ADVERTISING SIGN

Herbert G. Baumhoff, Washington, D. C.

Application June 30, 1939, Serial No. 85,790

Term of patent 14 years

To all whom it may concern:

Be it known that I, Herbert G. Baumhoff, a citizen of the United States, residing at Washington, D. C., have invented a new, original, and ornamental Design for Advertising Signs, of which the following is a specification, reference being had to the accompanying drawing, forming part thereof.

The dominant features of my design reside in the portions shown in full lines.

I claim:

The ornamental design for an advertising sign, substantially as shown and described.

HERBERT G. BAUMHOFF.
